UNITED STATES PATENT OFFICE.

JAMES GILCHREST, OF RAVENSWOOD, ILLINOIS.

MOWER.

SPECIFICATION forming part of Letters Patent No. 368,885, dated August 23, 1887.

Application filed October 11, 1886. Serial No. 215,930. (No model.)

To all whom it may concern:

Be it known that I, JAMES GILCHREST, a citizen of the United States, residing at Ravenswood, in the county of Cook and State of Illinois, have invented certain new and useful Improvements in Mowers, of which the following is a description.

This invention is an improvement upon my invention for raising the cutter-bar described in my Patent No. 347,481, dated August 17, 1886, and it relates particularly to the means for engaging the lifting mechanism with the driving-power and for locking the lifting mechanism to hold the bar elevated and disengaging it to allow it to fall.

In the drawings, Figure 1 is a plan. Fig. 2 is a sectional elevation from the stubble side of the inner wheel. Fig. 3 is a sectional elevation showing a modification of the mechanism for forcing the engagement of the lifting mechanism with the driving-power. Fig. 4 is an elevation in which is shown the modification contained in Fig. 3, and Fig. 5 a plan thereof.

A is the inner drive-wheel; A', the clutch-disk thereon, which has a notched periphery, A¹⁰, for the purpose of engaging the lifting mechanism. B is the axle, with which said disk is rigid.

The mower main frame comprises the tubular arm C', mounted on the axle, the forwardly-extended arm C², to which the cutter-mechanism frame is pivoted, the gearing-case C⁴, and the bracket C⁵, which has the upper channel, C⁶, in which the pole is secured. Rigid with the bracket C⁵ is the horizontal stem C⁶, which extends inward toward the vertical plane of the wheel A, and on the inner side of said stem is pivoted the bell-crank lever D. To the arm D' may be secured the lifting-lever D¹⁰, and to the arm D² is secured the rod D²⁰, which at the lower end is connected to the cutter-mechanism frame E. Said frame is hinged to the forward end of the arm C² of the main frame.

F is a lever pivoted concentrically with the axle B, connected at one end by the link F' to the arm D' of the bell-crank lever D, and having pivoted on the other end the dog F², which overhangs the notched rim A¹⁰ of the disk A', and is provided with the spring f²,

tending to hold it out of engagement with said notched rim.

G is a sliding bar which is connected at the forward end to the arm D² of the bell-crank lever D below the connection of said arm to the link D²⁰. From said connection the bar G extends rearward parallel with the tongue above the arm C' of the frame, passing through the loop or staple G', which is formed upon a bracket, C¹⁰, which is rigid with the main frame, and which is conveniently, also, as illustrated, made in the form of a notched segment, provided for locking the tilting-lever H at any convenient point rearward from the loop G'. A spring, G², is provided, reacting between the main frame and the bar G to sustain the rear end of said bar. Upon the upper edge of said bar it has the notch or mere shoulder g, which, when the bar is caused to slide rearward a sufficient distance, may become engaged with the loop G', and the spring G², by forcing the bar upward, tends to effect such engagement. From the rear portion of the bar G the horizontal stud G³ projects inward and across the vertical plane of the disk A', so that it may overhang the dog F² when the latter is at its rearmost position. Said bar may also be provided with a foot-rest, G⁴.

J is the driver's seat, secured in the usual position.

K is a cam rigid with some part of the main frame—conveniently with the bracket C¹⁰—and protrudes across the plane of the disk A' in front thereof, and in such position that the nose F²⁰ of the dog F² will be engaged by it and thereby forced out of engagement with the notched rim A¹⁰.

The action of this mechanism is as follows: When the finger-bar rests upon the ground, the bell-crank lever D and the parts connected therewith, including the dog F², are in the position shown in Fig. 1, the lever F being inclined to the rear, so that the dog F² is under the stud G³ and the sliding bar G is forward, the notch g being disengaged from and forward of the loop G'. When it is desired to lift the cutter-mechanism frame, the driver depresses the sliding bar G, which causes the stud G³ to encounter the dog F² and force it into engagement with the notched rim A¹⁰, which is revolving with the axle, and which,

when such engagement is effected, draws forward the upper end of the lever, to which the dog is attached—rocking the lever over the axle—carrying the lower end rearward, and by 5 means of the link F', attached to said lower end and to the arm D' of the bell-crank lever, rocking said lever over its pivot and causing the arm D² to rise and lift the cutter-mechanism frame. The same movement of the bell- 10 crank lever causes the bar G to slide rearward through the loop G' and bring the notch g behind the said loop by the time the dog F² has encountered the cam K and been thereby disengaged from the notched rim A¹⁰. The driver will have lifted his foot from the bar G as soon as engagement of the dog F² with the rim A¹⁰ was effected, and the bar having been caused to slide rearward, as described, the spring G² forces it upward as soon as the notch g reaches 15 the loop G', and by the engagement of the loop in said notch the bar is locked against returning forward when the disengagement of the dog F² from the rim A¹⁰ occurs, and renders such return otherwise possible. When it is 20 desired to lower the cutter-mechanism frame, an instantaneous stroke of the foot upon the bar G will disengage the notch from the loop, and the weight of the frame will cause it to fall and restore the connected mechanism to the initial position. Carelessness upon the 25 part of the driver in the use of this mechanism may cause him to continue the pressure of his foot upon the bar G after the engagement of the dog and notched disk has been effected until the same have been disengaged by the cam K, thus preventing the loop G' from becoming engaged in the notch g. This 30 will cause the cutter-mechanism frame to fall again immediately upon the re-engagement of the dog and notched disk, and if the pressure 35 of the foot is further continued it will be immediately raised again, because the bar G, sliding forward as the cutter-mechanism frame falls, will bring the stud G³ into position to engage the dog F², as it also returns to its 40 starting-point, and will force it again immediately into engagement with the disk and cause a repetition of the former movements. If it is desired to prevent this possibility, it 45 may be done by employing a lever, as L, pivoted on the frame above the axle, or at any convenient point where the driver's foot may rest upon it over the pivot, and said lever may have the forward end, L², extended so 50 that it overhangs the bar G and may be depressed upon it, and its rear end, L¹, extended so that it overhangs the dog F² in the position of the stud G³, which in that case is omitted from the bar G. 55

60 When it is desired to lift the cutter-mechanism frame, the driver will depress the rear end of the lever L, thereby causing the rear end, L¹, to effect engagement of the dog F² with the notched rim A¹⁰ and cause all the 65 movements before described accompanying the lifting of the cutter-mechanism frame by the revolution of said disk.

The depressing of the rear end of the lever L lifts the forward end, L², so that it will not prevent the bar G from being forced up by 70 the spring G² and being locked under the loop G'. The driver may therefore continue the pressure on the rear end of the lever L without causing the disengagement or preventing the engagement of the bar G, and 75 without therefore causing the cutter-mechanism frame to drop. When he desires to drop said frame, he will shift the pressure of the foot to the forward end of the lever L. This will disengage the bar from the loop and the 80 frame will fall. Such movement of the lever lifting its rear end carries it so high that it will not engage the dog F², when the latter returns to its initial position when the frame falls. The driver may therefore continue the 85 pressure on the forward end of the lever without damage.

I claim—

1. In combination with the main frame, the axle journaled therein, the cutter-mechanism frame hinged thereto, a lever pivoted on the main frame and connected to the cutter-mechanism frame to lift the same, a lever pivoted about the axle and connected to the lifting-lever, means, substantially as described, for locking the second-named lever to and disengaging it automatically from the axle, and a notched bar, as G, connected to and reciprocated horizontally by the lifting-lever, a stop, as the loop G', on the main frame to engage 100 its notch, and a spring reacting between the main frame and the notched bar to force the latter into engagement with the stop, substantially as set forth.

2. In combination with the main frame, the axle journaled therein, the cutter-mechanism frame hinged thereto, a lever pivoted on the main frame and connected to the cutter-mechanism frame to lift the same, a lever pivoted about the axle and connected to the lifting-lever, means, substantially as described, for locking the second-named lever to and disengaging it automatically from the axle, and a notched bar, as G, connected to and reciprocated horizontally by the lifting-lever, a stop, as the loop G', on the main frame to engage 110 its notch, and a spring reacting between the main frame and the notched bar to force the latter into engagement with the stop, and a lever, as L, pivoted on the frame and engaging the bar G when rocked in one direction, and when rocked in the other direction actuating the mechanism which locks to the axle the lever pivoted thereon, substantially as set 115 forth.

3. In combination with the main frame, the axle journaled therein, the cutter-mechanism frame hinged thereto, a lever pivoted on the main frame and connected to the cutter-mechanism frame to lift the same, a notched disk 120 revolved by the axle, a lever pivoted about the axle, a dog pivoted thereon in a position to engage the notches of the disk and provided with a spring to hold it out of such en- 125

gagement, a notched bar, as G, connected to and reciprocated horizontally by the lifting lever, a stop on the frame to engage the notch, and a lever, as L, pivoted on the frame and engaging the bar G when rocked in one direction, and when rocked in the other direction engaging the dog to force it into engagement with the notched disk, substantially as set forth.

In testimony whereof I have hereunto set to my hand, this 27th day of August, A. D. 1886, in the presence of two witnesses.

JAMES GILCHREST.
